UNITED STATES PATENT OFFICE

147,525

DESIGN FOR A PIN

Marcel Boucher, New York, N. Y.

Application August 14, 1946, Serial No. 132,498

Term of patent 7 years

(Cl. D45—19)

To all whom it may concern:

Be it known that I, Marcel Boucher, a citizen of the United States, residing in New York city, in the county of New York and State of New York, have invented a new, original, and ornamental Design for a Pin, of which the following is a specification, reference being had to the accompanying drawing, forming part thereof.

Fig. 1 is a front view of a pin showing my design, and

Fig. 2 is the side view thereof.

I claim:

The ornamental design for a pin, substantially as shown.

MARCEL BOUCHER.
